SUPPORT FOR TELEPHONE RECEIVER

James David Paterson, 211 Wonham St. S.,
Ingersoll, Ontario, Canada

Filed Nov. 20, 1973, Ser. No. 417,608

Term of patent 14 years

Int. Cl. D14—03

U.S. Cl. D26—14 A

FIG. 1 is a perspective view of the support for telephone receiver with the receiver and a portion of a wall shown in broken lines for illustrative purposes only;

FIG. 2 is a front elevation view of the support;

FIG. 3 is a rear elevation view of the support;

FIG. 4 is a top plan view of the support; and

FIG. 5 is a side elevation view of the support, as seen from the left hand side of FIG. 2.

I claim:

The ornamental design for a support for telephone receiver, as shown.
